No Drawing. Filed Sept. 21, 1962, Ser. No. 225,386
9 Claims. (Cl. 167—65)

This invention relates to producing anti-inflammatory activity in living bodies.

As anti-inflammatory agents, there have been mostly used adrenocorticoids such as cortisone, hydrocortisone, prednisone and prednisolone. However, these adrenocorticoids generally exhibit undesirable side actions, when continuously administered for a long time. Because of the drawback present in adrenocorticoids, there have been proposed and made available some non-adrenocortical anti-inflammatory agents such as acetylsalicylic acid, gentisic acid, 2 - (β - chloroethyl) - 2,3 - dihydro-4 - oxo - 1,3 - benzoxazine, salicylamide, aminopyrine, phenylbutazone, sulfinpyrazone, quinacrine, chloroquine, hydroxychloroquine, amodiaquin, gold sodium thiosulfate and e-aminocaproic acid. However, these non-adrenocortical compounds are generally inferior to the said adrenocorticoids in anti-inflammatory activity. Therefore, it has been desired to realize any other non-adrenocortical compounds possessing a high anti-inflammatory activity as well as the adrenocorticoids.

As the results of the pharmacological investigation on a variety of heretofore known or novel quinuclidine compounds derived from a naturally existing cinchona alkaloid, quinine, it has been now discovered that the quinuclidine compounds, corresponding to the following formula:

wherein R is lower alkyl, phenyl or lower alkylphenyl, possesses a high anti-inflammatory activity. [It should be understood that there are actually two stereoisomers regarding the carbon atom accompanied by the asterisk (*) in the above formula, one of them being designated as "normal" and the other as "allo." However, it has been discovered by the inventors that the "allo" isomer scarcely shows anti-inflammatory activity. Accordingly, all the formulae employed in the present specification are intended to represent only the "normal" isomer.] It has been also discovered that the toxicity of the said quinuclidine compounds I can be remarkably decreased without a large depression of the desirable activity by their conversion into the N-oxides, corresponding to the following formula:

wherein R has the same significance as designated above.

Accordingly, a primary object of the present invention is to provide a preparation for anti-inflammatory administration which includes the said quinuclidine compound I or II or their salt with a non-toxic acid as an active ingredient. Another object of the present invention is to provide a process for anti-inflammatory activity in living body. A further object of the present invention is to provide a utilization method of the naturally-existing cinchona alkaloid, quinine. These and other objects will

2

be apparent to those skilled in the art to which the present invention pertains from the subsequent description.

The production of the quinuclidine compounds I from quinine can be illustratively shown by the following scheme:

wherein R has the same significance as designated above. All the compounds in the above scheme are known and can be prepared in a conventional manner [Heidelberger et al.: J. Am. Chem. Soc., 41, 819 (1919); Ochiai et al.: J. Pharm. Soc. Japan, 67, 101 (1947); Ochiai et al.: J. Pharm. Soc. Japan, 71, 260 (1951); Ochiai et al.: Pharm. Bull., 6, 212 (1958); Ochiai et al.: Pharm. Bull., 1, 156 (1953); Ochiai et al.: Pharm. Bull., 2, 128 (1954); Ishikawa: Pharm. Bull., 6, 71 (1958)].

The quinuclidine compounds I possess a high anti-inflammatory activity. For instance, the animal test data of the quinuclidine compound, corresponding to the following formula:

are shown in Tables I, II, III, IV, V and VI in contrast with some commercially available anti-inflammatory agents.

TABLE I.—EDEMA INHIBITION ACTIVITY TEST

Edema producing agent	Test compound	Dose (mg./kg. of body weight)	Average edema inhibition (percent)
Formalin	Compound Ia	5	43
		1	55
		0.5	8
	Chloroquine diphosphate	100	14
Dextran		50	4
		20	3
		5	48
	Compound Ia	1	32
Histamine		0.5	12
	Chloroquine diphosphate	100	22
		50	2
		20	0
Serotonin	Compound Ia	5	46
		2	35
		1	29
	Chloroquine diphosphate	100	9

NOTE.—The rats were subcutaneously pretreated with the test compound and then subcutaneously administered the edema producing agent. The produced edema was measured and compared with that produced without pretreatment. The average edema inhibition shows that from one to three hours after the administration of the edema producing agent.

In the above table, it is shown that the edema inhibition activity of the compound Ia is more than 100 times that of chloroquine diphosphate, when subcutaneously administered to rats.

TABLE II.—EDEMA INHIBITION ACTIVITY TEST

Test compound	Dose (mg./kg. of body weight)	Average edema inhibition (percent)		
		Time after administration of formalin (hour)		
		1-3	4-6	7-9
Compound Ia	40	39	20	18
	20	32	29	18
Chloroquine diphosphate	10	17	20	8
	500	20	12	6
	250	16	12	5
	100	18	12	13

NOTE.—The rats were orally pretreated with the test compound and then subcutaneously administered formalin. The produced edema was measured and compared with that produced without pretreatment.

Thus, the edema inhibition activity of the compound Ia is at least 10 times that of chloroquine diphosphate, when orally administered to rats.

TABLE III.—EDEMA INHIBITION ACTIVITY TEST

Test compound	Dose (mg./kg. of body weight)	Average edema inhibition (percent)		Edema producing agent	
		Time after administration of edema producing agent (hour)			
		1-3	4-6		
Aminopyrine	50	16	7	Formalin	
Compound Ia	0.5				
Aminopyrine	50	5	1	Dextran	
Compound Ia	0.5	8	5		
Aminopyrine	50	22	10	Dextran	
Compound Ia	0.5				
Aminopyrine	50	9	2	Dextran	
Compound Ia	0.5	12	5		

NOTE.—The rats were subcutaneously pretreated with the test compound and then subcutaneously administered the edema producing agent. The produced edema was measured and compared with that produced without pretreatment.

From the above table, it can be said that the compound Ia is at least 100 times as effective as aminopyrine in the edema inhibiting action, when subcutaneously administered to rats. Adding to this, it can be also said that they exhibit a total activity, when administered together.

TABLE IV.—ANTI-INFLAMMATORY EFFECT

Edema producing agent	Formalin, ED ₅₀ (mg./kg. of body weight)	Croton, ED ₅₀ (mg./kg. of body weight)
Test compound:		
Chloroquine diphosphate	97.5	97.5
Compound Ia	1.2	1.1

NOTE.—The test compound was subcutaneously administered to mice. For the comparison of the effect, there was employed Trypan Blue test.

Thus, the anti-inflammatory effect of the compound Ia is approximately 100 times that of chloroquine diphosphate, when subcutaneously administered to mice.

TABLE V.—GRANULATION INHIBITION ACTIVITY TEST

Test compound	Total dose (mg./rat)	Weight of granulation (mg.)
Control	0.6	201.5±21.7
Hydrocortisone acetate	4.8	218.3±18.5
Compound Ia	0.06	143.4±16.0
	0.15	222.8±18.7
	0.3	181.8±14.1
	0.6	143.5±13.9
	2.4	142.4±6.0
		130.0±5.0

NOTE.—Granulation was produced by embedding formalin-soaked filter paper-pellet into the lacrimal-ventral region of rats. Then, the test compound was subcutaneously administered once daily for 6 days. Twenty-four hours after the last administration, the animals were killed and the granulations weighed.

It is clear that the potency of the compound Ia is approximately 8 times that of hydrocortisone acetate in the granulation inhibiting action.

TABLE VI.—TOXICITY IN RATS

Test compound	LD ₅₀ (mg./kg. of body weight)	
	Subcutaneously	Orally
Chloroquine diphosphate	187.2	884
Compound Ia	34.8	103

From the above table, it can be said that the compound Ia is much more toxic than chloroquine diphosphate, i.e. 5.5 times at the subcutaneous administration and 8 times at the oral administration.

Summarizing the above animal test data, it is concluded that the compound Ia is more toxic than the commercially available anti-inflammatory agent, e.g. chloroquine di-phosphate, but the former is remarkably more effective than the latter. Thus, the quinuclidine compounds I are the non-adrenocortical anti-inflammatory agents which can be used safely, compared with the heretofore known non-adrenocortical anti-inflammatory agents.

As disclosed above, the quinuclidine compounds I have a relatively high toxicity, but, the toxicity can be decreased by their conversion into the corresponding N-oxides. The quinuclidine-N-oxide compounds II are novel and can be produced by subjecting the quinuclidine compounds I to oxidation according to a per se conventional manner. For instance, the quinuclidine compound I is treated with hydrogen peroxide in acetic acid at room temperature (10 to 25° C.) whereby the quinuclidine-N-oxide compound II is prepared. The quinuclidine N-oxide compounds II are less toxic than the quinuclidine compounds I, the former being parallelly less potent than the latter in anti-inflammatory activity. For instance, the animal test data of the quinuclidine-N-oxide compound, corresponding to the following formula:

are compared with that of the quinuclidine compound Ia in Tables VII and VIII.

TABLE VII.—EDEMA INHIBITION ACTIVITY TEST

Test compound	Dose (mg./kg. of body weight)	Average edema inhibition (percent)		
		Time after administration of formalin (hour)		
		1-3	4-6	7-9
Compound Ia	5.0	43	10	1
Compound IIa	50.0	26	18	12

NOTE.—The rats were subcutaneously pretreated with the test compound and then subcutaneously administered the edema producing agent. The produced edema was measured and compared with that produced without pretreatment.

TABLE VIII.—TOXICITY IN MICE

Test compound	LD ₅₀ (mg./kg. of bodyweight) intravenously
Compound Ia	2.0
Compound IIa	42.3

Thus, the quinuclidine-N-oxide compounds II are less toxic and less potent than the quinuclidine compounds I. But, they are still remarkably active, compared with the heretofore known anti-inflammatory agents. Therefore, they are useful as non-adrenocortical anti-inflammatory agents can be employed safely, too.

For the preparations of the present invention, there are equally employed the quinuclidine compounds I or the quinuclidine-N-oxide compounds II or their salts with non-toxic acids. As the salts, there may be exemplified those with hydrochloric, hydrobromic, sulfuric, acetic, lactic, succinic, tartaric, citric, ascorbic, cinnamic, salicylic or 4-aminosalicylic acid. Of these salts, the salicylic acid addition salt is particularly preferred in easy crystallizability.

The active medicaments, e.g. the quinuclidine compounds I or their salts with non-toxic acids, are administered in dosage unit form, as carried by a suitable pharmaceutical carrier, to living bodies particularly for the relief of rheumatism. Normally, the preparation is orally administered, although they are just as effective when

otherwise administered. They may be administered in various dosages such as 3, 5, 10, 15, 20, 25 or 30 milligrams, although the unit dosage range may vary more broadly from about 1 to about 100 milligrams and preferably from about 5 to about 30 milligrams. They may be added to or otherwise used with various pharmaceutical carriers. By way of exemplification, various solid carriers may be employed such as lactose, mannitol, cornstarch, talc and magnesium stearate as well as other tabletting aids and fillers. If desired, some other ingredients such as hydrocortisone, prednisolone, aminopyrine, chloroquine and the like may be mixed with the said active medicaments. The medicinal mixture may then be tableted or encapsulated in a hard gelatine capsule, depending on the commercial unit form desired. Ordinarily tabletting is preferred. The amount of carrier or diluent may vary, according to tablet size desired or whether the dosage is made up in encapsulated form, from zero amount to the maximum amount consistent with the practical limits of bulk for a dosage unit. Normally the carrier with which the medicament is mixed does not exceed about 300 to about 500 milligrams.

In the similar manner, the quinuclidine-N-oxide compounds II or their salts with non-toxic acids can be administered in dosage unit form to living bodies.

The following are typical examples of preparations embodying the present invention.

Example 1

	Kilograms
4-(3-ethylquinuclidin-8-yl)-4-hydroxy-3-(2-toluenesulfonamido-5-methoxyphenyl)-butanol	1.00
Lactose	8.47
Cornstarch	3.48
Magnesium stearate	2.60

The foregoing are mixed together and slugged. The slugs are crushed and passed through a 30 mesh screen. The resulting granules are mixed with magnesium stearate (2.45 kilograms) and tableted in the usual way to give 100,000 tablets. Each tablet weighing 180 milligrams contains 10.0 milligrams of the active ingredient.

Example 2

	Kilograms
4-(3-ethylquinuclidin-8-yl)-4-hydroxy-3-(2-toluenesulfonamido-5-methoxyphenyl)-butanol salicylate	12.73
Lactose	20.00

The foregoing are mixed and granulated with a 10% acacia solution and dried. The granule is forced through a 16 mesh screen, and thereafter is mixed with the following:

	Kilograms
Sodium lauryl sulfate	0.20
Magnesium stearate	1.00
Amylum solani	q.v. to 37.50

This mixture is tableted in the usual way to give 100,000 tablets. Each tablet weighing 37.5 milligrams contains 12.73 milligrams of the active ingredient (equal to 10 milligrams of the free base).

Example 3

To a solution of 4-(3-ethylquinuclidin-8-yl)-4-hydroxy-3-(2-toluenesulfonamido-5-methoxyphenyl)-butanol (300 mg.) in glacial acetic acid (2.5 ml.), there is added 30% hydrogen peroxide (0.3 ml.), and the resultant solution is allowed to stand for 24 hours at room temperature. Then, 30% hydrogen peroxide (0.3 ml.) is further added to the solution and allowed to stand for 48 hours at room temperature. The reaction mixture is adjusted with 10% aqueous sodium hydroxide to alkalinity and shaken with chloroform. The chloroform layer is washed with water and dried over anhydrous sodium sulfate. Removing the solvent from the chloroform layer, the residue is crystallized.

lized from a mixture of acetone and ether to give 4-(3-ethylquinuclidin-8-yl)-4-hydroxy-3-(2-toluenesulfonamido-5-methoxyphenyl)-butanol-N-oxide (140 mg.) as white pillars melting at 228° C.

Analysis.—Calcd. for $C_{27}H_{38}O_5N_2S$: C, 62.55; H, 7.32; N, 5.41. Found: C, 63.05; H, 7.64; N, 5.44.

Example 4

To a solution of 4-(3-ethylquinuclidin-8-yl)-4-hydroxy-3-(2-toluenesulfonamido-5-methoxyphenyl)-butanol (0.2 g.) in ethyl acetate, there is added a solution of salicylic acid (0.026 g.) in ethyl acetate, and the resultant mixture is allowed to stand for 5 hours. Removing the solvent from the mixture, the residue is crystallized from a mixture of acetone and petroleum ether to give 4-(3-ethylquinuclidin-8-yl)-4-hydroxy-3-(2-toluenesulfonamido-5-methoxyphenyl)-butanol salicylate (0.16 g.) as crystals melting at 128° C.

Analysis.—Calcd. for $C_{27}H_{38}O_4N_2S.C_6H_6O_3$: C, 64.08; H, 7.18; N, 4.90. Found: C, 64.02; H, 7.71; N, 4.32.

What is claimed is:

1. Method of treating inflammation in the living animal body which comprises administering to said body an effective dose of the member selected from the group consisting of the compound of the formula:

wherein R is a member selected from the group consisting of lower alkyl, phenyl and lower alkylphenyl, the compound of the formula:

wherein R has the same significance as designated above and their salts with non-toxic acids.

2. Method of treating inflammation in the living animal body which comprises administering to said body an effective dose of the compound of the formula:

3. Method of treating inflammation in the living animal body which comprises administering to said body an effective dose of the compound of the formula:

4. Method of treating inflammation in the living animal body which comprises orally administering to said body an effective dose of the member selected from the group consisting of the compound of the formula:

wherein R is a member selected from the group consisting of lower alkyl, phenyl and lower alkylphenyl, the compound of the formula:

wherein R has the same significance as designated above and their salts with non-toxic acids.

5. Method of treating inflammation in the living animal body which comprises orally administering to said body an effective dose of the compound of the formula:

6. Method of treating inflammation in the living animal body which comprises orally administering to said body an effective dose of the compound of the formula:

7. Method of treating inflammation in the living animal body which comprises subcutaneously administering to said body an effective dose of the member selected from the group consisting of the compound of the formula:

wherein R is a member selected from the group consisting of lower alkyl, phenyl and lower alkylphenyl, the compound of the formula:

wherein R has the same significance as designated above and their salts with non-toxic acids.

8. Method of treating inflammation in the living animal body which comprises subcutaneously administering to said body an effective dose of the compound of the formula:

9. Method of treating inflammation in the living animal body which comprises subcutaneously administering to said body an effective dose of the compound of the formula:
